DESIGN FOR A COMBINED LIPSTICK AND VANITY CASE

Arthur R. Botham, New York, N. Y., assignor to Coty, Inc., Wilmington, Del., a corporation of Delaware

Application November 29, 1940, Serial No. 96,927

Term of patent 7 years

To all whom it may concern:

Be it known that I, Arthur R. Botham, a citizen of the United States, residing in the city and State of New York, have invented a new, original, and ornamental Design for a Combined Lipstick and Vanity Case, of which the following is a specification, reference being had to the accompanying drawing, forming a part thereof.

In the drawing:

Fig. 4 is side elevational view thereof with the centrally disposed lipstick member in raised position.

I claim:

The ornamental design for a combined lipstick and vanity case, as shown and described.

ARTHUR R. BOTHAM.
